UNITED STATES PATENT OFFICE.

MICHAEL A. FOSTER, OF ST. LOUIS, MISSOURI.

FURNACE.

SPECIFICATION forming part of Letters Patent No. 401,546, dated April 16, 1889.

Application filed December 8, 1888. Serial No. 292,999. (No model.)

To all whom it may concern:

Be it known that I, MICHAEL A. FOSTER, of the city of St. Louis, in the State of Missouri, have invented a certain new and useful Improvement in Boilers and other Furnaces, of which the following is a full, clear, and exact description, reference being had to the accompanying drawings, forming part of this specification.

10 This invention is in some respects an improvement on the invention for which Letters Patent No. 310,194 were granted me January 6, 1885, and in which a flue led from the front part of the ash-pit to the furnace-chamber, dis- 15 charging the air from the ash-pit upon the top of the fire.

In my present invention there is a flue extending from the ash-pit and extending upward in the front wall of the furnace between 20 the feed-doors, branching out above the doors and extending along both sides of the boiler to the rear end. The flue has a number of discharge-nozzles through which the air is forced into the fire-chamber by a steam-jet 25 centrally placed in each air-nozzle. The vertical part of the flue passes through the grate-bearing bar and has adjustable support thereon.

Figure I is a transverse section of a boiler- 30 furnace with the improvement applied thereto at line I I, Fig. II. Fig. II is a detail longitudinal section on line II II, Fig. I. Fig. III is a detail section at III III, Fig. I. Fig. IV is an end view of the transverse flue. Fig. V is a detail section at V V, Fig. IV. Fig. VI is a detail perspective view showing part of the vertical flue and grate-bearing bar. Fig. VII is a reduced horizontal section at VII VII, Fig. I. Fig. VIII is a horizontal section, also 35 taken on the lines VII VII, Fig. I, but showing a modification.

In the main the boiler-setting may be of a usual character. The front wall is seen as 1, having the fire-doors 2, through which coal is 45 fed to the fire.

3 is the fire-chamber, and 4 the grate-bars. 5 is the front grate-bearing bar, whose body is shown with a width equal to the thickness of the front wall, 1, and which has a channel 50 flange or lip, 6, on which rest the front ends of the grate-bars, the said ends being hooked at 7 to engage in the channel-flange, as seen

in Fig. II. The body of the bearing-bar is built into the front wall, while the flange 6 extends beyond the inner face of the wall. 55

8 is the vertical part of an air-flue, which is built into the front wall, and which has lateral branches 9 at top, extending through the front and side walls, 10, to the outside of the latter, where they have stoppers 11, which 60 may be removed to give access to the flue for cleaning, &c.

12 are side flues extending through the side walls to the rear end of the boiler-setting, where they have valves 13, by which their 65 ends may be wholly or partly closed. The air enters the vertical flue 8 through its open lower end, 14, which communicates with the ash-pit 15.

16 is a valve or damper by which the flue 70 may be partly or wholly closed. The flue has brackets 17, whose feet 18 rest upon the grate-bearing bar 5, so as to support the flue in proper relative altitude with the grate-bars and the boiler 19. The flue, with or without 75 its branches 9, is cast in one piece. In setting boilers the distance between the grate-bars and the boiler varies in different cases, and as the flue has support on the grate-bearing bar it is requisite that the brackets should be 80 adjustable, so as to properly place the branches 9 and other parts relatively to the boiler, and for this purpose the brackets are adjustably attached to the flue by screws 20, which pass through vertical slots 21 in the brackets and 85 screw into the flue. A single bracket may be used in place of the two. The flue 8 passes through an aperture made in the front side of the bearing-bar.

22 is a steam-pipe, which is shown passing 90 beneath the flange 6 of the bearing-bar 5 to a point in front of the flue, from whence it extends through the front wall of the flue and upward through this flue to the branch flue 9, through which it extends in branches 23, that 95 extend to near the end of the branch flues 9, where they have removable caps, so that access may be had to the interior of the branch pipes for the purpose of cleaning them.

From the vertical flue 8 and branches 9 extend nozzles 24, which pass through the part of the front wall between the flues and the fire-chamber and discharge air into the chamber. From the vertical part of the steam-pipe 100

22 and its branches 23 extend steam-nozzles 25, which are axially placed in the air-nozzles 24, so as to form injectors, by which mingled steam and air are injected into the fire-chamber. The steam-pipe is governed by a valve, 26. The device is shown as applied to a boiler-furnace, but may be used for furnaces in general, the steam-pipe not being essential to it in its most simple form.

10 In the modification shown in Fig. VIII the steam-jets 27 are inserted in the ends of the branch flues 9, and the steam-pipe 22, with its branches, may be dispensed with, the steam-jets causing a suction in the side flues, 12, and causing the air to enter at their rear ends 15 and pass through the flues 9 and 8 and nozzles 24 into the fire-space. In this case the damper at the bottom of flue 8 is closed, so that no air enters at that point.

20 I claim as my invention—

1. The air-flue 8, leading from the interior of the ash-pit up the front of the fire-chamber and having side branches, 9, and having nozzles discharging into the fire-chamber.

25 2. The grate-bearing bar having a flange for support of the ends of the grate-bars, an aperture for the passage of an air-flue reaching from the interior of the ash-pit in front of the fire-chamber and having nozzles discharging from the flue into the fire-chamber.

30 3. The combination, with a grate-bearing bar and an air-flue extending from beneath the fire in front of the fire-chamber and discharging therein, of brackets adjustably attached to the flue and resting on the bearing-bar, substantially as and for the purpose set forth.

40 4. The air-flue opening beneath the fire within the ash-pit, extending upwardly in front of the fire-chamber and having nozzles discharging into the fire-chamber, and a steam-pipe having steam-nozzles within the air-noz-

zles forming injectors, by which the air is mixed with the steam and injected into the fire-chamber, substantially as set forth.

45

5. The air-flue extending from beneath the fire and upward in front of the fire-chamber and having side branches, the upright pipe and branches having nozzles discharging into the fire-chamber, and a steam-pipe extending through said flue and its branches and having steam-nozzles within the said air-nozzles and forming with such nozzles injectors forcing air mixed with steam into the fire-chamber.

50

6. The combination, with a boiler-furnace, of the upright flue 8, branch flues 9, and longitudinal flues 12, with valves 13 and 16 to govern the air-supply, and discharge-nozzles extending from the flue to the fire-chamber, and a steam-pipe passing through the upright and branch pipes and having nozzles within the nozzles of the air-flues 8 and 9, substantially as and for the purpose set forth.

60

7. The combination, with the vertical air-heating flue in the front of a fire-chamber having nozzles discharging into said chamber, and a port, 14, opening into the ash-pit, and a steam-pipe within said flue having steam-jet nozzles within the air-discharge nozzles, substantially as and for the purpose set forth.

70

8. The combination, with the furnace-wall, of a vertical flue in said wall having nozzles projecting through said wall into the furnace, 75 a grate-bearing bar let into said wall and having an aperture for the passage of the flue and grooves or channels 6, and the grate-bars 4, having hooks resting in said groove, substantially as set forth.

MICHAEL A. FOSTER.
